STOMACH TUBE

Original Filed Dec. 12, 1927

James A. Wilkins, INVENTOR
BY Victor J. Evans

WITNESS:

ATTORNEY

UNITED STATES PATENT OFFICE

JAMES A. WILKINS, OF NORFOLK, VIRGINIA

STOMACH TUBE

Application filed December 12, 1927, Serial No. 239,536. Renewed March 29, 1929.

This invention relates to such tubes as are used for insertion downward through the mouth and esophagus into the stomach for ascertaining the nature of the contents of the stomach for diagnostic purposes or for passing liquid downward into the stomach for lavage or for feeding the patient.

The object of the invention is to provide such a tube in simple form and of large flow capacity relative to the diameter of the tube. A further object of the invention is to provide such a tube with its lower end so loaded with weight material as to adapt that material to cause the tube to slide downward by gravity action on the lower part of the tube.

In the accompanying drawings,

Figure 1 is a longitudinal, sectional view through the improved tube; Figure 2 is a detail view showing the weighted part detachably joined to the rest of the tube;

Figure 3 is a section on the line, 3—3, of Figure 1, showing lateral ports;

Figure 4 is a view similar to Fig. 2, and showing shot or other pieces of metal used as the weight producing means.

In the drawings, 1 illustrates the structure consisting of a tube made of soft and flexible rubber, its upper end being thickened as shown at 2 for the attachment of an aspirator or funnel. A diaphragm or partition, 4, also preferably formed of rubber, is placed in the tube and firmly attached 30 to the walls thereof. This diaphragm is located far enough from the closed lower end of the tube to form a chamber, 5, at the lower part of the tube for receiving a body of mercury (quicksilver) or other heavy material 35 forming a body or mass which is not rigid.

When inserted at the beginning of the esophagus, this weighted end of the tube will slide downward and draw the tube downward through the esophagus until the lower end 40 of the tube is in the stomach or the duodenum, this movement being effected by gravity without the necessity of using a stylet or other device for inserting the tube. The part of the structure above the diaphragm is the main 45 part of the structure. Above and near the

weighted part, the wall of the main part is provided with holes or ports, 6, for the entrance of stomach or duodenal contents or for the exit of a fluid when the structure is used for treatment by lavage or for feeding 55 a patient.

In Fig. 1, the walls of the chamber, 5, are integral with the body of the tube, 1.

In Fig. 2, a supplemental tube section, 7, is substituted for the chamber, 5, of Fig. 1. 60 The lower end of the tube and the upper end of said section are each closed by a transverse wall. A bolt, 8, extends through said transverse walls, the head, 9, of the bolt being in the section, 7, and the nut, 10, being in the 65 lower end of the tube, 1. This auxiliary section is preferably made of the same diameter as the body of the tube, 1, and also of rubber, in order that it will be pliable like the tube, 1. The section, 7, is also to receive mercury. The mercury being a liquid—non-rigid—the chamber, 5, and also the section, 7, may bend as required while being inserted 70 for use.

In Fig. 4, the structure is the same as in 75 Fig. 2, excepting that the mercury is omitted and lead shot or other loose pieces of heavy material adapted to move on each other are substituted, the pieces of material allowing the section, 7, to bend as permitted by the 80 walls of said section.

The material used for adding weight to the lower end of the tube (Fig. 1) or the section attached thereto (Figs. 2 and 4) 85 should be mobile or movable on itself when confined within the chamber, so that the weight containing member may, during its downward or upward movements, readily shape itself to the curves of the throat, 90 esophagus, stomach and duodenum.

Since the weighted part of the structure is flexible or pliable, it may be made long enough to provide sufficient weight.

It is to be noted that the tube is of soft 95 and flexible rubber throughout; that there is no metal at the exterior of the tube to injure the mucous membrane of the stomach or duodenum as the metal tips of tubes in common use can do. There is no metal tip 100

which can become separated and get into a bronchus.

The holes or ports, 6, for entrance of the gastric or duodenal contents have rubber margins, and therefore no reasonable amount of suction at the upper end of the tube can injure the adjacent mucous membrane, as may occur with tubes having metal tips in which the corresponding holes have metal boundaries.

At the ports or holes, 6, the liquid contents of the stomach or duodenum pass through the tube more rapidly with the same amount of suction at the free end by means of an aspirator than is the case in the types of stomach tubes in common use; for the lumen of the ports, 6, is large enough and the ports are of sufficient number to allow easy flow into the tube. But the lumen of each port is less than the lumen of the tube. That precludes entrance of lumps or masses of food or mucus into the tube large enough to lodge in and obstruct the tube. Thus aspiration is facilitated.

Since the tube is sufficiently weighted at its lower end by mercury (quicksilver) or other suitable weight material, a wire stylet, such as is usually placed into the ordinary flexible rubber stomach tube to facilitate its passage by means of pressure from above by the operator, is unnecessary. Consequently the danger of puncture of the wall of the esophagus or stomach by the lower end of the stylet leaving the tube through either an opening already in the tube or through an opening accidentally made, does not exist.

The tube can be used for diagnostic aspiration of the stomach or duodenal contents or for internal lavaging or for feeding an unconscious patient, without any downward force being applied from above by the operator, since the weight at the lower end of the tube together with peristalsis will insure rapid downward passage of the tube. This minimizes the disagreeableness of the process, of which patients almost always complain.

This tube meets less resistance during its downward movement than is the case in the ordinary type of stomach or duodenal tube, since, in my tube the diameter is small, that being permitted because the lumen is large in proportion to the diameter. The diameter need not be more than a fourth of an inch, while on some other stomach tubes the tips are more than one-fourth of an inch in diameter.

While, as above stated, my tube is large enough to be used for gastric diagnosis or for duodenal lavage or for feeding through a funnel attached to the free end of the tube, it is small enough for diagnostic aspiration with a syringe.

This tube is simple of construction and it is, for that reason, easy to keep clean.

I claim as my invention:

1. A stomach tube structure comprising a flexible weighted lower part and a flexible main part having ports above and near the weighted part.

2. A stomach tube structure comprising a flexible weighted lower part and a flexible main part having ports above and near the weighted part, the diameter of the weighted part and the diameter of the main part being substantially the same.

3. A stomach tube structure comprising a flexible weighted lower part and a flexible main part having ports above and near the weighted part, the lumen of the individual ports considered separately being less than the lumen of the main part of the structure.

4. A stomach tube structure comprising a flexible weighted lower part and a flexible main part having ports above and near the weighted part, the lumen of the individual ports considered separately being less than the lumen of the main part of the structure but the aggregate lumen of the ports being as large as the lumen of said main part.

5. A stomach tube structure comprising a flexible tube closed at its lower end, weight material in the lower end, a partition above the weight material, the tube wall having ports above and near said partition.

6. A stomach tube structure comprising a flexible tube closed at its lower end, weight material in the lower end, a partition above the weight material, the tube wall having ports above and near said partition, and the lumen of the ports considered separately being less than the lumen of the tube above the ports.

In testimony whereof I affix my signature.

JAMES A. WILKINS.
